US00D918393S

(12) **United States Design Patent** (10) Patent No.: **US D918,393 S**
(45) Date of Patent: **** May 4, 2021**

(54) **PAIR OF ELECTRODE PADS**

(71) Applicant: **Sanofi**, Paris (FR)

(72) Inventor: **Julia Geissen**, Paris (FR)

(73) Assignee: **Sanofi**

(**) Term: **15 Years**

(21) Appl. No.: **29/633,220**

(22) Filed: **Jan. 12, 2018**

Related U.S. Application Data

(62) Division of application No. 29/579,018, filed on Sep. 27, 2016, now Pat. No. Des. 816,227.

(30) **Foreign Application Priority Data**

(57) **CLAIM**

The ornamental design for a pair of electrode pads, as shown and described.

DESCRIPTION

FIG. 1 is a perspective view of a pair of electrode pads showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 3 Drawing Sheets
